UNITED STATES PATENT OFFICE

LINDSAY THORNE CRABBE, OF CHICAGO, ILLINOIS, ASSIGNOR TO PHOENIX-HERMETIC COMPANY, OF CHICAGO, ILLINOIS, A CORPORATION OF NEW YORK

JAR CLOSURE

Application filed March 24, 1930. Serial No. 438,540.

The invention relates to new and useful improvements in jar closures, and more particularly to a jar closure which includes a cap secured to the jar by a sealing band which 5 overlies the cap and is adapted to be turned underneath the ledge on a jar.

An object of the invention is to provide a closure structure whereby a uniform pressure may be applied both to the cap and the overlying portion of the sealing band in the region directly above the lip of the jar for holding said cap in sealing engagement with the jar while the band is being crimped underneath the holding lip on the jar.

10 A further object of the invention is to provide the cap with a recess formed in the outer surface thereof adjacent the periphery whereby the overlying portion of the band will be housed therein with the outer face of the 15 overlying portion substantially flush with the outer face of the cap.

A still further object of the invention is to provide a closure for jars wherein the cap is formed with an inwardly projecting annular bead disposed adjacent the inner wall of the jar on which the cap is to be used whereby a channel is formed in the cap for confining the sealing material to the region directly above the lip of the jar with which sealing 20 contact is made.

These and other objects will in part be obvious and will in part be hereinafter more fully disclosed.

In the drawings:—

25 Figure 1 is a view showing partly in side elevation and partly in section a jar closure embodying the improvements applied to a jar.

Fig. 2 is a view in section showing a cap 30 or cover for a jar having the improvements applied thereto.

Fig. 3 is a sectional view through a closure showing the same applied to a jar and with the chuck brought into engagement therewith 35 for seating the cover preparatory to the securing of the same to the jar.

Fig. 4 is a view similar to Fig. 2, but showing the closure fully seated, sealed and joined to the jar.

40 The invention is directed to a closure for

jars, bottles or the like, and more particularly to a jar closure which includes a cap or cover portion secured to the jar by a sealing band. The sealing band is provided with a laterally projecting flange adapted to overlie the cap 55 and the lower edge of the band is turned underneath a holding ledge on the jar. Thus it is that the cap is secured to the jar and the jar closed. This is an ordinary form of jar closure.

45 The invention is directed particularly to the construction of the cap. The cap is provided with a recess in its outer face at the periphery of the cap which is so proportioned as to provide a housing for the overlying 60 flange portion of the sealing band so that the outer face of the flange portion is substantially flush with the outer face of the cap. The cap is also provided with an annular bead disposed adjacent the inner edge of the 65 lip of the ordinary jar so as to produce in the cap a channel for the confining of the sealing material so that the sealing material will be disposed substantially above the lip of the 70 jar with which sealing engagement is to be 75 made.

50 Referring more in detail to the drawings, the invention is shown as applied to a jar which is indicated at 1 in the drawings. The jar has a sealing lip against which the sealing 80 material is pressed and a holding ledge 2 underneath which the band is turned for securing the cap or cover to the jar. The cap is indicated at 4 in the drawings. The cap is made of thin sheet metal. The cap has the usual 85 depending flange 5 at its periphery. The cap also is formed with an annular depression 6 in its outer face which is of a depth substantially equal to the thickness of the metal constituting the holding band. The holding 90 band is indicated at 7 in the drawings. Said band has the usual overlying flange 8 which engages the cap for drawing the cap into sealing contact with the jar. This overlying flange 8 is housed in the recess 6 and the inner 95 edge of the overlying flange is in a measure concealed by the shoulder 9 of the cap. This inner edge of the overlying flange is formed by cutting the metal and the steel plate thus exposed sometimes corrodes and becomes un- 100

sightly. In the present construction where this raw edge of the metal is substantially concealed by the shoulder in the cap, the unsightly appearance is avoided. Furthermore, by forming the recess so that it is of a depth substantially equal to the thickness of the metal forming the overlying flange the chuck which is illustrated at 9 in the drawings will make contact with the outer face of the overlying portion of the band and also with the outer face of the cap, as clearly shown in Figs. 3 and 4.

The cap 4 is also provided with an annular bead 10. This annular bead is disposed back a slight distance from the periphery of the cap so that the outer curved wall 11 of the bead forms with the depending flange 5 of the cap a channel 12 for the sealing material which is indicated at 13 in the drawings.

The sealing material is applied to the cap in a fluid or plastic form while the cap is inverted with the channel facing upward. These inner and outer walls of the channel confine the sealing material so that it forms a relatively thick sealing gasket which is disposed so as to make contact with the outer sealing surface of the lip of the jar. The outer face of the central portion of the cap 4 is substantially flush with the outer face of the portion of the cap directly over the channel so that when the chuck moves down against the cap, it engages the cap firmly not only in the central portion but directly above the sealing material, and it also engages the overlying flange of the sealing band and thus it is that the entire closure may be pressed against the lip and the lip firmly embedded in the sealing material and a tight seal held while the lower edge of the closure band is spun underneath the holding lip 2 as indicated at 14 in the drawings.

In Fig. 3 the cap is shown as loosely applied to the jar and the chuck as moved down into engagement with the cap ready to force it into sealing contact with the jar. In Fig. 4 the cap has been forced down into sealing contact with the jar and the lip of the jar embedded in the sealing gasket and the lower edge of the band has been spun underneath the holding ledge on the jar, and thus the closure secured to the jar. The band used for securing the cap to the jar is preferably of the breakable type and is provided with a lifting tongue 15 and a holding lug 16. This means for joining the ends of the band may be of any desired construction.

While the cap with the improved features thereof is shown as used in conjunction with a sealing band, it will be understood that other types of holding means may be provided.

Having fully described my invention, what I claim as new and desire to secure by Letters Patent, is:—

1. A closure for jars or the like comprising a yieldable disc-like cap having a depending flange and a channel for retaining a plastic sealing gasket therein, said cap having a recess for receiving and housing an overlying flange of a sealing band for binding the cap to the jar and sealing the same. 70

2. A closure for jars or the like comprising a yieldable disc-like cap having a depending flange and a depending annular bead spaced from the flange and forming a channel for retaining a plastic sealing gasket therein, said cap having a recess for receiving and housing an overlying flange of a sealing band for binding the cap to the jar and sealing the same. 75

3. A closure for jars or the like comprising a yieldable disc-like cap having a depending flange and a channel for retaining a plastic sealing gasket therein, a sealing band for binding the cap to the jar, said band having a flange overlying the cap and said cap having a recess for receiving and housing the overlying flange of the band with the outer face of the flange substantially 90 flush with the outer face of the cap. 85

4. A closure for jars or the like comprising a yieldable disc-like cap having a depending flange and a depending annular bead spaced from the flange and forming a channel for retaining a plastic sealing gasket therein, a sealing band for binding the cap to the jar, said band having a flange overlying the cap and said cap having a recess for receiving and housing said overlying flange with the outer face of the flange substantially flush with the outer face of the cap. 95

In testimony whereof, I affix my signature.

LINDSAY THORNE CRABBE.
